UNITED STATES PATENT OFFICE.

CLAUDE A. BROOKS AND EVAN G. KINLEY, OF TOPEKA, KANSAS.

PRIMER FOR GASOLENE-ENGINES.

1,072,304.

Specification of Letters Patent.

Patented Sept. 2, 1913.

Application filed April 5, 1912. Serial No. 688,631.

To all whom it may concern:

Be it known that we, CLAUDE A. BROOKS and EVAN G. KINLEY, citizens of the United States, residing at Topeka, in the 5 county of Shawnee and State of Kansas, have invented certain new and useful Improvements in Primers for Gasolene-Engines, of which the following is a specification.

10 Our invention relates to primers to be used for starting gasoline engines.

It is a well known fact that much cranking is usually required in order to secure a proper supply of gas from the carbureter, 15 in starting, especially in cold weather; principally on account of the carbureter being located some distance from the intake valves and on account of the first suction in the operation of the pistons taking in only 20 air.

We are aware that attempts have been made in various ways to prime the cylinder or the inlet pipe with gasoline; but in our invention, we provide a primer comprising a tube 25 entering through the wall of the inlet pipe and terminating in a spray nozzle in the mixing chamber immediately under and adjacent to the intake valve. By this arrangement, we prevent undue flooding of 30 the cylinder with the gasoline or gas, and insure a proper mixture of the gas and the air coming in initially through the inlet pipe, on the initial suction of the cylinder.

In the drawing accompanying and forming 35 part of this specification and in the description of the drawing, we have shown our invention in its preferred form, and have shown what we deem to be the best mode of applying the principles thereof; but it is to 40 be understood that, within the scope of the appended claims, we contemplate changes in form, proportions, and materials, the transposition of parts, and the substitution of equivalent members, without departing 45 from the spirit of our invention.

The drawing is a vertical sectional elevation of a single cylinder of a gasoline engine, showing also the intake valve, the mixing chamber under the valve, and the 50 inlet pipe leading from the carbureter to the mixing chamber, with our priming device applied thereto.

1 is the casing for the cylinders and water circulation, 2 is one of the cylinders, 3 is the 55 cylinder head, 4 is the mixing chamber under the intake valve 5, 6 is the valve stem, 7

is the intake or inlet pipe, also called the manifold in multiple cylinder engines, leading from the carbureter to the mixing chamber. This much is old in the art.

Through the wall of the inlet pipe at the 30 top of the elbow 8, where the inlet pipe turns from vertical to horizontal disposition, we insert a small tube 9, through a suitable bushing 14, which tube extends 35 into the mixing chamber, having an inward and upward bend and terminating in a spray nozzle 10 immediately adjacent to and below the intake valve. The tube leads, as indicated somewhat diagrammatically at 73 11, from a small tank 12, from which the gasoline flows to the nozzle by gravity. The tube is provided with a cock 13. Normally, the cock 13 is closed, so that no gasoline is furnished to the engine through the 75 tube 9. In starting the engine, the cock is opened momentarily, but only long enough to permit a small supply of gasoline to flow into the tube or to permit the gasoline to overflow the tube, the surplus dropping into 80 the mixing chamber below the valve. Now, the first suction from the cylinder will draw a mixture of the air which is in the inlet pipe and the gas from the gasoline with which the mixing chamber has been primed, 85 in just about the same proportions as they are normally drawn from the carbureter, and the charge so drawn into the cylinder will burn from the first spark. In this connection, we desire to state that this mixture 90 is not secured when the gasoline is introduced into the cylinder initially for priming, as the mixture may be too rich or too weak. Nor, on the other hand, is priming in the inlet pipe sufficient to insure starting on 95 the first charge, since even in such case, it may require more than the first charge to secure the proper mixture. But by introducing the priming charge into the mixing chamber and immediately adjacent to the 100 intake valve, we are certain that the very first charge drawn in through the intake valve will start the engine, as the surplus gasoline let in through the priming tube if there be any surplus, will not flood the 105 cylinder or the valve, and the whirling motion induced by the suction through the intake valve will draw in both air and gas and at the same time mix the same thoroughly.

110 While we have shown our primer applied to a single cylinder, it is to be understood

that it may be applied as well to multiple-cylinder engines, either by using a separate priming tube for each intake valve where each intake valve has an individual mixing chamber, or by using a priming tube for the two intake valves in each pair of cylinders where the cylinders are arranged in pairs with a single mixing chamber for each pair of intake valves; and in any case a single tank and cock may be used with branch tubes leading to each primer. It is also to be understood that the ordinary priming charge let into the tube or overflowing into the mixing chamber will be sufficient to charge the cylinder many times, and to keep the engine running long enough to secure the drawing of a proper mixture from the carburetor. It will also be therefore further understood that where a primary or storage battery is used or available for the sparking, the engine may be frequently started by turning on the spark, having charged the mixing chamber first. This would occur where the engine had stopped with any of its cylinders charged and in position for sparking, as the explosion in any one of multiple cylinders equipped with our primer, would insure running the engine until the carburetor would furnish the proper mixture, even under unfavorable conditions.

What we claim is:

1. The combination with a casing having a cylinder and a mixing chamber, an intake valve above the mixing chamber, and an inlet pipe leading from the carburetor to the mixing chamber and having an elbow close to the point of junction with the mixing chamber, of a tube passing through the wall of the inlet pipe on top of the elbow and having an inward and upward bend and terminating in a spray nozzle in the mixing chamber and immediately adjacent to and below the intake valve, a supply tank located at a higher level than the nozzle and connected with said tube, and a cock for controlling the flow through said tube.

2. In a gasoline engine, the combination with a cylinder, a mixing chamber under the intake valve, said intake valve, and an inlet pipe leading from the carburetor to the mixing chamber, of a priming tube passing through the wall of the inlet pipe and having an inward and upward bend and terminating in a spray nozzle within the mixing chamber and adjacent to and below the intake valve, a supply tank located at a higher level than said nozzle and connected with said priming tube, and a cock for controlling the flow in said tube.

3. In a gasoline engine, the combination with a cylinder, a mixing chamber, an intake valve above the bottom of the mixing chamber, and an inlet pipe leading into said mixing chamber, of a priming tube passing through the wall of the inlet pipe and passing into and terminating with an upward bend and a spray nozzle within the mixing chamber and adjacent to said valve, a source of supply for said tube, and a means for controlling said supply.

4. In a gasoline engine, the combination with a cylinder, a mixing chamber, an intake valve above the bottom of the mixing chamber, and an inlet pipe leading into the mixing chamber, of a priming tube passing into said mixing chamber and terminating in an upward bend and with a spray nozzle adjacent to said valve.

5. In a gasoline engine, the combination with an inlet pipe adapted to connect the carburetor with the mixing chamber, of a tube passing through the wall of said pipe and having an upward bend projecting beyond the end of the pipe, which end is adapted to be adjacent to the intake valve when the pipe is applied to the engine casing.

In testimony whereof we have affixed our signatures in presence of two witnesses.

CLAUDE A. BROOKS.
EVAN G. KINLEY.
